(57) **CLAIM**

The ornamental design for an engine cylinder valve spring compressor tool, as shown and described.

DESCRIPTION

FIG. 1 depicts a perspective view from the side and front of the invention.

FIG. 2 depicts a front elevational view of the invention of FIG. 1.

FIG. 3 depicts a back elevational view of the invention of FIG. 1.

FIG. 4 depicts a side elevational view of the invention of FIG. 1.

FIG. 5 depicts a top plan view of the invention of FIG. 1; and,

FIG. 6 depicts a bottom plan view of the invention of FIG. 1.
